UNITED STATES PATENT OFFICE.

EDWIN T. KERSHAW, OF DENVER, COLORADO.

INTERNAL-COMBUSTION ENGINE.

1,394,094.

Specification of Letters Patent. Patented Oct. 18, 1921.

Application filed May 20, 1919. Serial No. 298,402.

To all whom it may concern:

Be it known that I, EDWIN T. KERSHAW, a citizen of the United States, residing at Denver, in the county of Denver and State 5 of Colorado, have invented certain new and useful Improvements in Internal-Combustion Engines; and I do hereby declare the following to be a full, clear, and exact description of the invention, such as will enable others skilled in the art to which it 10 appertains to make and use the same.

This invention relates to internal combustion engines and more particularly to the two-stroke cycle type of engine.

15 The present invention has direct relation to that type of two-stroke cycle internal combustion engines in which means are employed to form, independently of the crank case, a preliminary compression space or 20 chamber from which the compressed fresh fuel charges are led or directed into the usual combustion chamber of the engine.

It is one of the objects of the present invention to provide for the efficient and maximum 25 introduction of fresh fuel charges into the preliminary compression space. A further object of the invention is to improve this type of engine so as to eliminate the use of the crank case as a compression space and 30 therefore overcome the requirement for packing the sections of the crank case as is usually necessary in order to hold the compressed fresh charges. A further object 35 of the invention is to provide a simple, practicable, substantial, efficient and durable means, capable of being readily arranged within a hollow piston in the engine cylinder with the dual objects of forming with the piston a preliminary compression chamber 40 and also for admitting to this compression chamber successive charges of fresh gaseous fuel.

With these and other objects in view as will 45 become manifest to those versed in the art from the following disclosures, the invention consists of the construction, the combination, and in details and arrangements of the parts as more particularly described in the following specification relative to the embodiment 50 of the invention disclosed in the accompanying drawings wherein:

Figure 1 is a vertical, central section through a cylinder and the piston thereof in a plane parallel to the axis of the motor 55 shaft.

Fig. 2 is a vertical, central section through the engine organization in a plane at right angles to that of Fig. 1.

Fig. 3 is a cross-section on line 3—3 of Fig. 1.

While I have shown the invention in the present case as embodied in an engine of only one cylinder and its piston, it is obvious that multiple units may be employed and further that various other modifications, 65 alterations and changes within the spirit of the invention may be resorted to within the scope of the appended claim.

An engine is illustrated as including a suitable casing or cylinder 2 which is provided 70 with means constituting a by-pass indicated at 3 having a portion registerable with an outlet port 3^a formed in the wall of a hollow piston 5 shown as provided with a removable head 5^a which is upwardly bulged or deflect- 75 ed to form a deflector for incoming charges of fresh fuel leaving the by-pass 3 at the port 3^b thereof. As is common to this type of engine, suitable exhaust means, as the outlet port 6, are provided, ports 6 and 3^b 80 being uncovered by the head of the piston when the latter is in its lowermost position as shown in Fig. 1 at which time a compressed charge of gaseous fuel is emitted under high pressure through the port 3^a 85 from a preliminary compression space 4 which is formed between the head 5^a and an abutment or head member 8.

The abutment or head 8 is shown as provided with a downwardly extending support 9 forming a pipe or passage which is provided at its lower end with any suitable means for fastening it to or mounting it upon a stationary portion as for instance the engine casing. This hollow or tubular 95 support not only serves the purpose of a mounting for the fixed abutment head 8 but is also utilized as a means for conveying gaseous fuel from a suitable source which is connected thereto as by the outwardly ex- 100 tended portion 10 at the lower end of the support 9. In certain instances, according to the construction of the lower end of the piston 5, its cylindrical wall may be cut away as at 11 to form a clearance for the 105 outwardly extending portion 10 of the support in the event that in the organization the lower end of the piston 5 would have to pass a contiguous portion of the support 9—10.

As the piston 5 moves upwardly the head 5^a thereof moves away from the head 8, the tendency to create a vacuum in the space 4 resulting in the opening of a puppet valve 12 mounted upon and opening upwardly from the head 8 thus admitting a supply of fuel from the source, through hollow support 9 to space 4; the valve being provided with a light return or re-seating spring 13 of just sufficient strength to cause the valve to seat as soon as the pressure of the incoming fuel thereon is overcome but not before an ample and sufficient charge of fuel has been drawn into the preliminary compression space or chamber 4. It will be understood, of course, that as the piston 5 moves upwardly its port 3^a cuts off the flow of fuel through the by-pass 3 and on the downward movement of the piston the compression charge is compressed in the space between the heads 5^a—8 and when the port 3^a again registers with the inlet of the by-pass 3 the compressed fuel may be expelled rapidly at considerable pressure into the combustion chamber in an ample and sufficient quantity.

From the above it will be seen that by a proper and easily determined regulation of the valve spring and proper proportioning of the port area and the volume of the preliminary compression space 4, the valve 12

can be controlled to such a nicety, as will insure the introduction of a full charge of fuel into the preliminary compression space and therefore irrespective of the speed of the engine a sufficient charge can be introduced into the combustion chamber to secure an improvement in the efficiency of engines of this kind.

It will also be evident that while the foregoing description refers to the admission of combustible fuel into the preliminary compression space, this construction may be as readily used with heavy fuels where the fuel is injected into compressed air in the combustion chamber, the air alone (instead of the combustible mixture) being subjected to preliminary compression.

What I claim is:

In an internal combustion engine having a sliding piston with an internal compression chamber, the combination of a head for said compression chamber having an orifice therethrough, valve means mounted in said orifice and a hollow bracket member having a flanged open end conforming to said orifice adapted to seat under the same to support the head, said hollow bracket constituting a conduit to supply fuel to the said compression chamber.

In testimony whereof I affix my signature.

EDWIN T. KERSHAW.
